by Walter P. Geyer
Attorney.

UNITED STATES PATENT OFFICE

HARVEY E. HERR, OF BUFFALO, NEW YORK, ASSIGNOR TO HERR MANUFACTURING COMPANY, INC., OF BUFFALO, NEW YORK, A CORPORATION OF NEW YORK

SPINNING RING

Application filed April 13, 1931. Serial No. 529,607.

This invention relates generally to the spinning rings employed in connection with spinning machines, and more particularly to improvements in the combined construction of the spinning ring and its holder.

One of the objects of the invention is to provide a self-contained spinning ring wherein a positive and uniform bearing for the bar traveler is provided, and which is so constructed that it is not liable to become warped or distorted.

A further object is to provide a self-lubricating spinning ring of this character which is simple, efficient and inexpensive in construction, and whose guide or bearing elements for the bar traveler are formed as an integral part of the ring to produce an annular bar-receiving space or channel which is concentric with the operating spindle of the machine and which is constantly maintained uniform and thereby insures a true bearing for the bar traveler at all times.

In the accompanying drawing:—

Figure 1 is a top plan view of a spinning ring and its holder constructed in accordance with my invention. Figure 2 is an enlarged transverse section thereof taken on line 2—2, Figure 1. Figure 3 is an enlarged fragmentary transverse section taken on line 3—3, Figure 1. Figure 4 is a top plan view of the supporting base or holder for the spinning ring.

Similar characters of reference indicate corresponding parts throughout the several views.

In spinning machines of the character to which my invention is particularly applicable, the threads to be twisted are delivered by feed rolls (not shown) to a take-up spool 10 mounted on a revolving spindle and traversing the same is a vertically reciprocating bar 11, the spool extending through an opening 12 in the bar, as seen by dotted lines in Figure 2.

Mounted on the reciprocating bar 11 and surrounding the take-up spool 10 is the supporting member or holder for the spinning or traverse ring upon which the customary bar traveler 13 is adapted to revolve. During the operation of the machine, the bar traveler as-

sumes a substantially upright position and revolves with and about the take-up spool, the thread passing under the traveler before being wound upon the spool and the traverse bar 11 being reciprocated so that the threads 55 are uniformly wound in layers upon the spool.

The holder which supports the ring is preferably stamped or formed from sheet metal and consists of an annular attaching base 14 having a central opening 15 therein through which the spool 10 is adapted to extend, and at its outer edge it is provided with a pair of oppositely facing slotted ears 16 for securely fastening it to the bar 11 in any approved 60 manner. Rising from the outer edge of this base are yieldable brackets 17 for detachably receiving and holding the spinning ring in place on the holder.

In its preferred form, the spinning ring 70 for guiding the bar traveler about the take-up spool consists of a self-contained unit adapted to be mounted on the holder in frictional engagement with its yieldable brackets 17, and is composed of an annular base member or ring 18 of U-shaped or trough-like cross section, the outer wall 19 thereof being adapted to contact with the holder-brackets and the inner wall 20 thereof being slightly flared upwardly and outwardly to form a 80 guide flange or neck for the spinning ring. As shown in Figure 2, the bottom of the base member of the spinning ring rests on the top side of the holder 14, and its inner wall or neck 20 is substantially concentric or axially 85 aligned with the holder-opening 15. In order to lubricate the traveler 13, the ring-base is adapted to contain a supply of lubricant, as indicated at 21.

Overhanging the open top side of the 90 trough-shaped ring 18 is a bearing flange 22 with which the depending legs of the bar traveler are adapted to engage in the manner shown in Figure 3. This bearing flange is provided with a depending annular attaching flange 23 which is fitted within the bearing ring and securely fastened to the outer wall 19 thereof, as by a pressed fit. The bearing flange 22 is preferably flared outwardly, 95 as seen in Figures 2 and 3, and terminates at 100

its inner edge short of the opposing or adjoining upper edge of the inner wall or neck 20 of the ring 18 so as to provide an annular channel or passage 24 for receiving the 5 pending legs of the bar traveler. The bearing flange 22 is hardened and polished on its bearing faces and its inner edge is preferably rounded as indicated at 25 to form a track or bearing face for the bar traveler. The upper 10 edge of the wall 20 of the ring is likewise rounded and its bearing surface is hardened and polished. It will be noted that the bottom wall of the ring and the overhanging bearing flange 22 thereof are at a fixed distance 15 from each other to freely accommodate the bearing ends of the bar-traveler.

By this construction, a spinning ring is provided wherein the annular space 24 for the bar traveler is maintained constant and 20 uniform, the elements constituting it being an integral and self-contained part of the spinning ring and separate from the holder 14. Furthermore, the construction is such that the inner wall or neck 20 of the ring 25 positively limits the inward tipping movement of the bar traveler and prevents the same coming in contact with the bobbin and injuring the thread. In addition to these 30 features, provision is made for effective lubrication of the bar traveler, the latter being adapted to dip into the lubricant contained in the ring from time to time, and in so doing the construction of the ring is such 35 that any surplus oil is prevented from being thrown out onto adjoining bobbins.

I claim as my invention:—

1. A device of the character described, comprising a flat, flangeless supporting member containing a central opening and having 40 brackets rising from the outer edge thereof, and a self-contained spinning ring detachably mounted on said supporting member between its brackets and including an annular trough-like member adapted to receive a lubricant and a bearing flange for a bar traveler extending inwardly from the outer wall of said trough-like member toward the inner wall thereof and disposed 45 in concentric spaced relation thereto, the bottom of the trough-like member resting flatwise on said supporting member.

2. A device of the character described, comprising a supporting member having a 55 central opening therein and brackets rising from the outer edge thereof, and a self-contained spinning ring for a bar traveler mounted on said supporting member between its brackets and including a lubricant-receiving base-ring of substantially U-shape in cross-section and a bearing ring for the bar traveler overhanging the open top of said base ring and terminating at its inner edge 60 short of the opposing upper end of the 65 inner wall of the base ring to form an an-

nular channel for receiving the legs of the bar traveler.

3. A device of the character described, comprising a supporting member consisting of a flat ring having brackets rising from 70 the outer edge thereof, and a self-contained spinning ring for a bar-traveler mounted on said supporting member in contact with its brackets and including inner and outer concentrically spaced guide elements for the 75 traveler, said spinning ring having a flat bottom resting on said supporting member, and the inner guide element of the spinning ring being substantially in line with the supporting ring opening. 80

4. A device of the character described, comprising a supporting member containing a central opening and having brackets rising from the outer edge thereof, the remaining portion of said member being substantially 85 flat and free from projections and a substantially trough-shaped, self-contained spinning ring for a bar traveler detachably mounted on said supporting member with its bottom resting flatwise thereon and its periphery in engagement with the brackets thereof, said ring including inner and outer concentrically spaced guide elements for the traveler. 90

5. A device of the character described, comprising a flangeless holder-ring having brackets rising from adjacent its periphery, and a spinning ring for a bar traveler detachably mounted in flatwise overlying engagement with said holder-ring and having 95 its periphery in engagement with said brackets, and including an annular trough-like member adapted to receive a lubricant and a bearing flange for a bar traveler overhanging said trough-like member and terminating at its inner edge in spaced concentric relation to the inner wall of the trough-like member. 100

6. A device of the character described, comprising a flat supporting member having 110 brackets rising therefrom outwardly of its periphery, and a self-contained spinning ring for a bar traveler detachably mounted on said supporting member with its bottom in flatwise engagement therewith and its periphery in engagement with said brackets, and including integral guide elements disposed at substantially right angles to each other and terminating short of their adjoining free edges to provide an annular channel 115 for the legs of the bar traveler. 120
